UNITED STATES PATENT OFFICE.

HARRY A. LEONARD, OF HOPEDALE, MASSACHUSETTS, ASSIGNOR TO DRAPER CORPORATION, OF HOPEDALE, MASSACHUSETTS, A CORPORATION OF MAINE.

BUILDER MECHANISM FOR WINDING MACHINES.

Application filed February 26, 1923. Serial No. 621,210.

This invention relates to builder mechanisms for yarn winding machines whereby yarn is laid upon yarn receivers or bobbins for subsequent use.

5 It is now the usual practice to wind yarn upon yarn receivers or bobbins with a reserve supply or "bunch" as it is sometimes called, for subsequent use in feeler looms, so that when the feeler mechanisms of such 10 looms call for replenishment of filling, a full length of filling may be laid in the shed on the last pick of the shuttle preceding filling replenishment.

In a prior application filed by Charlie 15 A. Payne, Serial No. 612,267, a builder mechanism was shown and described for placing upon yarn receivers or bobbins a reserve supply of filling in the form of a cylindrical bunch and on the completion of the bunch to 20 pass at once to the regular service traverse. Such form of bunches or preliminary windings are advantageous in connection with certain characters of yarn or types of feeler mechanisms, but with other characters of 25 yarns or types of feeler mechanisms, and for the additional purpose of producing a wound filling carrier or bobbin of the desired form, it is preferable to provide a reserve supply of filling or bunch which will merge into 30 the regular traverse wind, and the present invention is therefore a further development of the type of builder mechanism shown and described in the application referred to, and wherein a bunch builder mechanism has 35 been devised for placing the windings of yarn upon yarn receivers or bobbins with a final traverse which merges into the regular service traverse on the completion of the bunch.

40 In accordance with the present invention the builder arm of the usual builder mechanism has mounted thereon a rocking member provided with an involute surface which is engaged by an actuator or other member 45 of the bunch builder mechanism which in cooperation with the involute surface of the rocking member shall provide a reserve supply of filling or bunch on the filling carriers or bobbins, the traverse of which will gradually merge into the regular service traverse.

More specifically stated, though without limitation as to details of the bunch formation, the present invention winds upon the filling carriers or bobbins the preliminary 55 layers of yarn without traverse and the sub-

sequent windings of yarn with a traverse which merges into the regular service traverse.

The various novel features of the present invention and the new combinations of parts 60 will best be made clear from the following description and the accompanying drawings of the builder mechanism provided with a good practical form of the present invention.

In the drawings:

Fig. 1 is a perspective view of a winding machine having the present invention associated therewith;

Fig. 2 is a detached detail in side elevation showing portions of the builder mechanism 70 and the present invention by full lines in the relative position they occupy during regular service traverse;

Fig. 3 is a similar view to that of Fig. 2 showing the relation of parts when the machine has been stopped and the builder arm has been depressed; and

Fig. 4 is a graphic illustration of a filling carrier or bobbin showing the form of the reserve supply of filling.

A builder mechanism with the present invention associated therewith is shown as applied to a ring spinning machine of usual type whereby the yarn is spun and wound directly upon yarn receivers or bobbins, and 85 while the advantages of the present invention are clearly manifested by its use in such type of machine, it is to be understood that the invention is not restricted to a ring spinning machine but may be employed in connection with any character of winding machine wherein yarn is wound upon yarn receivers or bobbins.

In the drawings it has not been deemed necessary to illustrate the entire winding 95 or spinning machine, and only those parts are shown which are necessary for comprehensive understanding of the builder mechanism and the associated invention.

The end frames 1 of the machine are connected by cross ties 2 and a spindle rail 3 on which the spindles are mounted for rotative movement as usual. The ring rail 4 extends longitudinally of the machine and is provided at intervals with the usual rings upon 100 which are mounted the travelers 5 which constitute guides for directing the yarn to the yarn receivers or bobbins. These parts may be of usual construction and require no further illustration.

Mounted in the brackets 6 carried by one of the cross-ties 2 or the machine frame is the rock shaft 7 on which is mounted an arm 8 carrying a weight 9 for imparting lifting movement to the ring rail. The rock shaft 7 has secured to it a lifting arm 10 which, as usual, is shown as carrying a roller 11 upon which rests the foot 12 of the ring rail traversing rods 13, only one of which 10 is shown. The rod 13 extends upwardly and is secured to the ring rail 4. The rock shaft 7 has secured to it a third arm 14, in the present instance, to the upper portion of which is connected the chain or other flexible connection 15, the other end of which is connected to the builder mechanism for imparting to the ring rail its traversing movement longitudinally of the yarn receivers or bobbins, all as usual in this class of machines.

The chain 15 or other flexible connection passes over a guide pulley 16 and at its lower end is connected at 17 to the usual drum 18 secured to or formed as part of the back gear 19 mounted upon the builder arm 20. The builder arm 20 is pivotally supported upon a stud or dead shaft 21 carried by the machine frame and its rear end portion is provided with a weight 22 which is sufficient to normally over-balance the weight of the other end of the builder arm which carries a stud or roller 23, Fig. 3. Mounted upon the rotating shaft 24 which is supported by the machine frame is the usual builder cam 25 against the cam surface 26 of which the pin or roller 23 bears under the action of the weight 22 during regular service traverse. The shaft 24, as usual, is driven from a going part of the machine, but since the means for rotating the shaft 24 is old and well-known and the details of which form no part of the present invention, it is not herein shown and described.

Mounted in bearings 27 secured to the builder arm 20 is the worm shaft 28 carrying a worm 29 which meshes with the teeth of the gear 19, and secured to the end portion of the worm shaft is the pick wheel 30 which is stepped along at intervals by the usual pick mechanism, not here shown because it is of well known construction and the details thereof form no essential part of the present invention.

From the construction thus far described it will be apparent that as the builder cam 25 is rotated, the builder arm 20 will be given a rocking movement on its pivotal support 21 and will cause the ring rail 4 to be moved up and down or traversed by the cooperating lifting tendency of the weight 9 and the lowering tendency imparted from the builder cam 25. As the builder arm is thus rocked upon its support the pick wheel 30 is stepped along by the usual pick mechanism to let back on the chain or connection

15, thereby causing the ring rail or yarn guiding means to gradually progress upwardly on successive traverses, all as usual in this class of machines. The parts thus far described and their operation are old and well-known and constitute one good form of builder mechanism to which the present invention is readily applicable without substantial change in construction or reorganization of the builder mechanism and the parts constituting the same.

In accordance with the present invention, the builder arm carries a bunch builder member or segment having an involute bunch building surface, which at the commencement of the winding operation acts in conjunction with a circular member or actuator to lay a few preliminary or bunch winds upon the receivers or bobbins, and then complete the bunch with a traverse which merges into the regular service traverse as the bunch builder member or segment passes to an inoperative position.

In the form of the invention shown, the shaft 24 of the regular builder cam 25 has mounted thereon the toothed gear 31 of circular contour and such gear, in the present instance, is rotated in unison with the builder cam 25.

The builder arm 20 has the cooperating member or segment 32 connected thereto. In the present instance the builder arm 20 carries a bracket 33 from which projects the stud or shaft 34 on which the rocking member or segment 32 is conveniently mounted. The segment 32 is provided with an involute surface 35 which, during the bunch building operation, will cooperate with the circular member 31 to build a bunch in which the preliminary windings are laid upon the yarn receivers or bobbins without traverse and the succeeding layer or layers will be wound with a traverse that gradually merges into the regular service traverse under the dictates of the involute surface of the segment.

The involute surface of the segment 32, as shown, is provided with a series of teeth, during the bunch building operation, engage the teeth of the rotary gear 31. One portion of the involute surface of the segment, as between the points *a*—*b*, is formed on the arc of a circle of a uniform or constant radius, while the portion of the involute surface between approximately the points *b* and *c* is formed on a curve of different radius, for a purpose that will later appear.

Machines of the general type herein described are usually provided with a shipper mechanism or belt shipper for stopping the machine when the filling carriers or bobbins have been completely wound, and in accordance with the present invention, advantage is taken of this circumstance to condition a train of mechanism for moving the segment from its inoperative to its operative

position when the machine is stopped and the builder arm is depressed.

As shown in the present instance, the shipper mechanism comprises the rod 36 which may extend longitudinally of the machine in suitable bearings provided therefor. The rod 36 carries a belt shipper fork 37 for transferring the belt 38 from the fast pulley 39 to the loose pulley 40 and conversely. The shipper rod 36 may be conveniently operated from a shaft 41 which carries an arm 42 having a slot 43 into which projects a pin 44 carried by a yoke 45 secured to the shipper rod, as indicated in Fig. 1.

When the machine is in operation and winding the filling carriers or bobbins with a service traverse, the segment or rocking member 32 is in the position shown by full lines, Fig. 2, and as will be noted, is not engaged with the gear 31. When, however, the filling carriers or bobbins have been fully wound and the machine is stopped for doffing, it is desirable that the bunch builder mechanism shall be automatically positioned for commencing the winding of the next series of bobbins or filling carriers to build the bunch. To this end the machine frame has mounted thereon the segment controller 46 which is connected by a flexible member 47 to a spring 48, the flexible member between the controller 46 and spring being guided over a guide pulley 49, Fig. 1. When the machine is winding the filling carriers or bobbins with a full service traverse, the belt 38 is on the driving pulley 39 and the shipper rod 36 is in its left position, Fig. 1, so that the spring 48 is not tensioned. When, however, the shipper rod 36 is moved to the right, Fig. 1, to throw the belt onto the fast pulley and stop the machine, the spring 48 is placed under tension, and this tension is utilized in accordance with the present invention to throw the segment 32 into operative relation with the co-acting circular gear 31 when the machine is stopped and the builder arm is depressed.

In the present instance the actuator 46 is provided with a shoulder 50 on which the segment 32 normally rests while the machine is operating to lay the yarn upon the yarn receivers or bobbins with the regular traverse, as indicated in Fig. 2. When, however, the machine is stopped and the spring 48 is placed under tension, the governor 46 will be lifted and cause the segment 32 to be moved from its full to its dotted line position, Fig. 2, with the teeth of the involute surface of the segment contacting with the teeth of the rotary gear 31. When, now, the builder arm is depressed during doffing, as usual, the tension of the spring 48 still acting through the governor 46 will throw the segment 32 from its dotted line position, Fig. 2, to its full line position, Fig. 3, or in

other words, will place the segment in operative relation with its co-acting circular gear 31, and when the builder arm is allowed to rise, the teeth of the involute surface of the segment will engage the teeth of the rotary gear 31.

Since the involute surface 35 of the segment between the points *a* and *b* approximately, is formed on an arc of constant radius, it follows that during the time or interval that this portion of the involute surface is engaged by the cooperating member or gear 31, the builder arm will remain substantially stationary and the windings of yarn will be placed upon the yarn receivers or bobbins without traverse. This non-traversing movement is desirable in some forms of bunches and obviously the extent of volume of this portion of the bunch may be varied in accordance with the extent of arc, between the points *a* and *b*, traversed by the cooperating member or gear 31. As the segment is moved to the left, Fig. 1, by the cooperating member or gear 31, the unturned portion of the involute surface between the points *b* and *c* will traverse the gear 31 and the builder arm 20 will gradually rise with the result that the windings of yarn will now be laid upon the filling carriers or bobbins with an upward traverse which merges with the full regular traverse on completion of the bunch when the segment returns to its normal or inoperative position.

As indicated in Fig. 4, the bobbin or filling carrier 51 will have the bunch formed by preliminary windings without traverse, as as 52, and the final layers 53 constituting the bunch will have a traverse in one direction which gradually merges into the regular traverse.

It may be desirable at times to vary the size or character of the bunch and to this end the bracket 58 is provided with a flanged portion 54 in which is adjustably mounted a stop 55 for limiting movement of the segment 32 towards its operative relation with the co-acting gear 31. The stop 55 is preferably formed as an adjusting screw held in adjusting position by a lock nut 56 so that by adjusting the stop 55 the number of the preliminary or non-traverse winds placed upon the yarn receivers or bobbins may be varied.

Similarly, the flange 54 may be provided with a stop 57, Fig. 3, for limiting the movement of the segment 32 to its inoperative position.

From the construction described as constituting a good practical form of the present invention, it will be apparent that the preliminary windings which form the bunch may be laid upon the yarn receivers or bobbins without traverse and the succeeding windings which complete the bunch may be formed with a traverse in one direction.

which gradually merges into the same length as the regular traverse, and it will be equally obvious that upon variation in the involute contour of the segment that bunches of various kinds may be laid upon the yarn receivers or bobbins.

The present invention provides a simple efficient means for building bunches of the desired form upon yarn receivers or bobbins 10 which is readily applicable to a builder mechanism of usual construction without change in the builder mechanism itself.

What is claimed is:

1. In a machine of the class described, the 15 combination of yarn guides, a builder arm connected to the yarn guides, a builder cam, a gear rotatable with the builder cam, a segment pivotally mounted on the builder arm and having a toothed surface formed by 20 teeth of uniform depth which is engaged by said gear during the bunch building operation, one portion of the toothed surface being formed in the arc of a circle of greater radius than another portion to build a bunch 25 without traverse and then with a traverse in one direction which merges into the regular traverse, machine stopping mechanism, and means rendered operative by movement of the stopping mechanism to stopping position for moving the segment automatically 30 into bunch building position.

2. In a builder mechanism for winding machines, the combination of a builder cam and builder arm, yarn guiding means connected to the builder arm, a bunch builder segment pivotally mounted on the builder arm and having a toothed bunch building portion of non-circular contour, a rotatable member which is engaged by the non-circular 40 contour of the segment during bunch building operation, a segment controlled machine stopping mechanism, and connections between the machine stopping mechanism and segment for moving the segment into bunch 45 building position when the stopping mechanism is moved to stopping position for automatically winding the bunch when the machine is again started.

3. In a builder mechanism for winding 50 machines, a builder arm and builder cam, yarn guiding means connected to the builder arm, combined with a bunch builder mechanism including a bunch builder segment loosely mounted on the builder arm and having a toothed bunch builder surface, a segment actuator for cooperating with the segment to build a bunch with a plurality of windings without traverse and then with a traverse which gradually merges into the 55 service traverse stopping mechanism, and a spring which is tensioned by the stopping mechanism when the machine is stopped for moving the segment to operative position for building the bunch when the machine is 60 again started.

4. A winding machine, having, in combination, yarn guiding means, a builder arm connected thereto, a builder cam which acts through the builder arm to impart service traverse to the yarn guiding means, a rotary toothed gear of circular contour, a segment pivotally mounted on the builder arm to swing in a direction longitudinally thereof into and out of operative relation with the toothed gear and having a series of teeth, one 70 portion of the series being at a greater radial distance from the axis of the segment than another portion of the series, that a bunch may be built with a final traverse that merges into the regular service traverse 80 when the bunch is completed and the segment is moved out of operative relation with the gear and stops for confining the segment to a rocking movement in both directions on the builder arm to and from operative position.

5. In a machine of the class described, the combination of yarn guides, a builder arm connected to the yarn guides, a rotatable toothed gear, a toothed segment pivotally 90 mounted on the builder arm to oscillate first in one direction into operative relation with the toothed gear and then in the opposite direction out of operative relation therewith, means for limiting the oscillating 95 movement of the segment in each direction, and means connected to the builder arm for changing the amplitude of oscillating movement of the segment.

6. In a machine of the class described, the 100 combination of a builder arm, a builder cam, yarn guides connected to the builder arm, a toothed gear rotatable with the builder cam, a toothed segment mounted on the builder arm for oscillating movement first 105 in one direction for placing the toothed segment in operative relation with the toothed gear and then in the opposite direction by the toothed gear into inoperative position, machine stopping mechanism, and 110 means rendered effective by the stopping mechanism when the machine is stopped for oscillating the toothed segment towards operative position.

7. In a machine of the class described, the 115 combination of a builder arm, a builder cam, yarn guides connected to the builder arm, a toothed gear rotatable with the builder cam, a toothed segment mounted on the builder arm for oscillating movement 120 first in one direction for placing the toothed segment in operative relation with the toothed gear and then in the opposite direction by the toothed gear into inoperative position, machine stopping mechanism, and 125 means actuated through the stopping mechanism for oscillating the toothed segment into engagement with the toothed wheel.

8. In a machine of the class described, the 130

combination of yarn guides, a builder arm connected to the yarn guides, a rotatable toothed gear, a toothed segment pivotally mounted on the builder arm to oscillate about a fixed center first in one direction into operative relation with the toothed gear and then in the opposite direction out of operative relation therewith, and means for limiting the oscillating movement of the segment in each direction.

9. A bunch builder attachment for builder mechanism, comprising a toothed segment having an involute bunch building portion and adapted to be mounted upon the

regular builder arm to oscillate in one direction into bunch building position and then in the opposite direction out of bunch building position, a wheel of circular contour having teeth for engagement with the teeth of the oscillating segment and acting upon the involute portion of the segment in building a bunch and for oscillating the segment in said opposite direction into inoperative position.

In testimony whereof, I have signed my name to this specification.

HARRY A. LEONARD.
